UNITED STATES PATENT OFFICE

2,625,221

OVERDOOR

James H. McKee, Aurora, and Melvin E. Hartzler,
 Downers Grove, Ill., assignors to McKee Door
 Company, Aurora, Ill., a corporation of Illinois

Application September 15, 1948, Serial No. 49,428

5 Claims. (Cl. 160—209)

1

Our invention relates to overdoors and is more particularly concerned with overdoors of the type wherein the door is composed of a plurality of hingedly-connected sections mounted on rollers carried in tracks having vertical portions on each side of the door opening, horizontal portions above the opening, and curved portions connecting the vertical and horizontal portions.

In the installation of overdoors in garages and other types of buildings one of the commonest difficulties encountered is the lack of space above the door opening to accommodate the conventional overdoor having horizontal track portions located some distance above the door opening and requiring additional space above the tracks to provide for the swinging movement of the upper edge of the topmost door section as this section is swung from vertical to horizontal position. Numerous attempts have been made to design track type overdoors which require less head room above the door opening than that required by the conventional overdoor, but all of such low head-room type overdoors heretofore developed have had objectionable features which have limited their utility and general acceptance. One of the principal difficulties with the conventional overdoor has been the difficulty of changing or correcting in the field when the headroom is less than reported or less than that for which the tracks were designed.

An object of our invention is to provide a new and improved low headroom type of overdoor which avoids the difficulties of the prior art and is capable of universal application.

One of the disadvantages of the prior art structures has been the necessity for using generally U-shaped brackets attached to the bottom corners of the door and secured to the lower ends of the cables or flexible members connecting the door with the counterbalancing mechanism so that these cables or flexible members may be located outside of the tracks. An important feature of our invention lies in the construction and arrangement of parts whereby these cables or flexible members can be located between the edges of the door and the tracks and the use of such U-shaped brackets avoided.

Another object of our invention is to provide a new and improved low headroom type of door of such construction that the counterbalancing springs or other means may be located either above the door opening or at the rear of the horizontal track portions or in any other desired position.

Another object of our invention is to provide a

2

new and improved overdoor construction wherein the bottom door section either may remain in the curved portion of the track when raised or can be raised to the full horizontal position entirely within the horizontal portion of the track.

Another object of our invention is to provide a new and improved overdoor requiring less space than a standard installation.

Another common disadvantage of the low head-

10 room type of overdoors of the prior art resides in the necessity of providing special springs for moving the upper end of the topmost door section into door-closing position. An object of our invention is to provide a new and improved construction of overdoor whereby such springs are eliminated and the upper section is moved in door-closing and door-opening positions in a smooth and substantially noiseless manner.

Another disadvantage of some of the low head-
 20 room types of overdoors heretofore used resides in the fact that the upper section is not held firmly against the doorjamb with the result that the force of the wind or any other comparable force will move the door to partially open position. Another object of our invention is to provide a new and improved overdoor wherein the entire door is held firmly in closed position.

Another object of our invention is to provide a new and improved overdoor of the low head-
 30 room type wherein positive means is provided for turning the topmost section and the space required for such turning is a minimum.

Another object of our invention is to provide a new and improved overdoor which is readily
 35 adjustable to meet a wide variety of conditions.

Other objects and advantages will become apparent as the description proceeds.

In the drawings:

Fig. 1 is a partial rear elevation of an overdoor
 40 embodying our invention;

Fig. 2 is a sectional view taken on the line 2—2
 of Fig. 1;

Fig. 2 is a partial sectional view taken on the
 45 irregular line 3—3 of Fig. 2;

Fig. 4 is a side view on an enlarged scale of
 the tripper bracket and mounting therefor;

Fig. 4A is a sectional view taken on the line
 4A—4A of Fig. 4 showing a detail;

Fig. 5 is a sectional view of a sheave or idler;

Fig. 6 is a partial sectional view on an enlarged
 50 scale showing the position of the lower section
 of the door when the latter is in a raised position;

Fig. 7 is a partial sectional view taken on the
 same plane as Fig. 2 illustrating in greater detail
 55 the bracket construction and tripper mechanism

and also showing the counterbalancing spring located above the door;

Fig. 8 is a rear perspective view of a further embodiment of our invention utilizing a different counterbalancing mechanism;

Fig. 9 is an enlarged partial perspective view similar to Fig. 8 but showing the position of the upper section of the door during the initial opening movement thereof;

Fig. 10 is a perspective view looking in the same direction as Figs. 8 and 9 and showing the door in a fully raised position;

Fig. 11 is a rear elevational view showing in more detail the conventional hinge construction used; and

Fig. 12 is a partial sectional view taken on the line 12—12 of Fig. 11.

Referring particularly to Figs. 1 and 2, it may be seen that we have illustrated therein a multi-section door A which is adapted when in the lower or vertical position to close the door opening in a building B. A rail or track C is attached to the building B and has a vertical portion 10 extending downwardly adjacent one side of the door opening, a horizontal portion 12 located immediately above the door opening and a curved connecting portion 14. The sections of which the door is constructed may be of any desired or conventional type and are illustrated as having windows D.

The several sections are pivotally connected to each other as by hinges 16 adjacent the lateral edges of the door and each hinge is illustrated as carrying a roller 20 located in its adjoining track 10. The lower corners of the bottom section are provided with plates 18, each of which carries a roller 20 located in the adjacent track. These corner plates 18 also provide U-shaped anchors 22 for attachment of the usual pull ropes 24 whose other ends are usually attached to the building or tracks at the sides of the door opening by any suitable attaching means as, for example, the eyes 26.

It will be noted particularly from an examination of Fig. 2 that the vertical portions 10 of the tracks do not extend the full height of the door opening but terminate a substantial distance below the top of this opening. The curved track portions 14 which connect the vertical and horizontal track portions are located almost entirely in the rear of the upper door section 28 and extend upwardly only a short distance above the top of this section. By reference to Fig. 2 it will be readily apparent that when the upper door section 28 is in closed position the topmost edge of this section is spaced a substantial distance forwardly of the curved track portion 14 and an important feature of our invention lies in the mechanism for supporting and controlling the upper edge of this section.

In Figs. 1, 2, 3, 7, 8, and 9 there is best illustrated a plate 30 attached to each upper corner of the section 28 and having a sleeve 32 to which a first bracket 34 and a reinforcing strap 36 are pivotally connected by a bolt 38. A second or trolley bracket 40 is attached to the first bracket 34 and strap 36 by a bolt 42. In making the original installation the trolley bracket 40 can be swung about the bolt 42 to the proper position and then locked in this position by a second bolt 44 which passes through a bore in the trolley bracket 40 and an arcuate slot 46 in the first bracket 34. The first bracket 34 engages one side of the sleeve 32 on plate 30 and the strap 36 is bent so that one end engages the other side of

this sleeve 32 whereby the strap 36 and bracket 34 form a clevice.

The lower portion of the trolley bracket 40 is offset as indicated at 50 in Fig. 3 to clear the edge of the upper section of the door. This offset also functions as a stiffening means for the trolley bracket 40. A track roller 52 is mounted on a stud 54 attached to the trolley bracket 40 and this roller normally lies in the curved portion 14 of the track when the door is in closed position as best shown in Figs. 2 and 7. The trolley bracket 40 also carries a trolley 56 which preferably but not necessarily comprises two rollers (Fig. 1) mounted on a shaft 58 secured in the lower end of the trolley bracket 40.

The trolley 56, as best shown in Fig. 2, is controlled by an auxiliary track or tripper mechanism indicated generally by reference character 60 and carried by a tripper bracket 62 bolted or otherwise suitably secured to each of the tracks. This bracket 62 is best shown in Figs. 4 and 7 and has bolt receiving slots 64 facilitating adjustment of the bracket relative to the track so that smooth and quiet closure of the upper edge of the topmost door section can be assured. An auxiliary track is formed between a guide bar 66 and a tripper bar 68. The upper edge of the tripper bar 68 merges with the inner curve of its supporting track as indicated at 69 and where this merger occurs the end of the tripper bar 68 is preferably forked and inclined backwardly along each side of the track as best shown in Fig. 4A so that the trolley moves from the tripper bar into the track and vice versa smoothly and noiselessly.

It is customary to counterbalance the weight of such doors by means of springs or weights and to connect the counterbalancing means to the lower edge of the door by suitable cables, chains or ropes. In the drawings, we have illustrated such counterbalancing means as comprising a pair of helical spring assemblies 70, each assembly being mounted by a bracket 72 attached to the track. Each spring assembly consists of a coil spring and cable reel, the latter being indicated by reference character 74 (Fig. 1). A cable 76 is wound on the reel 74 and is connected to a plate 18 attached to a lower corner of the door, the attachment being effected by turning the lower end of the cable about a grooved anchor member 78 and securing the end of the cable by fastening it beneath the washer 80 carried by a bolt attached to plate 18. An intermediate portion of this cable in the particular arrangement shown passes over the sheave 82 mounted on the tripper bracket 62 and shown in more detail in Fig. 5.

An important feature of our invention lies in the fact that with our new and improved construction this cable is located in the vertical plane between the edge of the door and the adjacent track so that it is unnecessary to provide U-shaped brackets or other attachments fastened to the lower edge of the door and extending around the track for securing the lower end of the cable to the door. Such a location of the cable is made possible by the provision of the sheave 82 where the counterbalancing means is located at the rear of the track as shown in Fig. 2. In this connection it will be noted that when the door is in the fully raised position the cable may be out of contact with the sheave 82 but located thereabove (Fig. 6) so that when the door is returned to closed position the cable engages the sheave 82 and is guided thereby.

The more conventional location for a counterbalancing means such as the torsional spring 10 and reel assembly 74 is immediately above the door opening. Such a location is shown in Fig. 7 and is just as feasible with our new and improved door as with any standard door provided there is sufficient headroom above the door opening for such location of the spring assembly. When the spring assembly is located above the door opening the cables 76 can pass directly from the spring assembly to the securing plates on the door in the usual manner and will still be located in the planes between the edges of the door and the adjacent tracks.

In this Fig. 7 the dash line 84 indicates the path of travel of the forward upper edge of the upper section of the door of our invention, whereas the dot-dash line 86 indicates the path of travel of the corresponding edge of a conventional door with conventional top roller brackets. A comparison of these two paths of travel quickly and conclusively shows the outstanding merit in our invention in requiring far less headroom than is required by the conventional overdoor.

It is to be further understood that our novel door is not limited to use with any particular type of counterbalancing means but is adapted to use with a wide variety of such means. In Figs. 8, 9, and 10, we have illustrated a different form of counterbalancing means utilizing a tension spring 88 having its rear end 90 secured to any fixed support and its forward end 92 attached to a pulley 94 over which the cable 76a passes. The lower end of the cable 76a may be attached to the lower corner of the door in the same manner in which cable 76 is shown in Figs. 1 and 2 as being attached to its door, or in any other suitable manner, and the upper end of cable 76a is attached to the horizontal track or any other fixed support. A guide wire 96 may pass lengthwise through the tension spring 88 to reduce sagging thereof, the ends of the guide wire 96 being attached to any suitable fixed supports. The use of this guide wire is optional and may be omitted, as indicated in Fig. 10.

It will be best seen in Figs. 2, 7, and 8 that when the door is in the closed position the upper edge of the topmost section 28 is firmly held against the doorjamb by positive means and without the intervention of springs, weights, or other resilient or yielding mechanism. It is therefore not possible for a wind or any other similar force to move the door to a partially open position or to disturb the tight fit between the door and edges of the door opening.

When the door is raised the initial movement of the upper edge of the topmost section 28 is a hinged and pivotal movement about the roller 52 and trolley 56 which draws it in closely to the curved portion 14 of the track, as shown in Fig. 9. Such pivotal movement is caused by the engagement of the trolley 56 with the guide bar 66 which prevents the trolley 56 from moving upwardly until after the aforesaid pivotal movement has been effected. Thereafter, the upper edge of the section 28 swings in a curve closely following the curved portion 14 of the track so that a minimum of space is required for turning this section from a vertical to a horizontal position. This curving movement of the upper section is under the control of roller 52 in the curved portion 14 of the track and the trolley 56. In Fig. 2 the upper section 28

is shown in dot and dash lines in an intermediate position to illustrate more clearly the small space beyond the track which is needed for the turning movement of this section.

- 5 When the door is in the full open position the lowermost section may remain in the curved track portion 14 as shown in Fig. 6 or may rest in the horizontal track portion 12 as shown in Fig. 10, as desired. In either position the cable 10 76 or 76a serves to hold the door in elevated position and will re-engage the sheave 82 as the door is lowered.

When the door is lowered the lower sections are brought into engagement with the doorjamb 15 by providing a slight taper to the vertical portions of the track or in any other of the numerous ways for accomplishing such sealing. As the upper section is returned toward closed position the trolley 56 engages the tripper bar 68 which is so curved that as further movement of the section occurs the trolley bracket 40 and attached bracket 34 pivot around track roller 52 and gently but positively swing the upper edge of the section 28 into closed position. In this 20 connection it will be noted that the trolley 56 is positively controlled at all times properly to regulate the swinging movement of the upper edge of the door section about track rollers 52 and that this control is effected noiselessly and 25 without the interposition of springs or other yielding means.

Referring to Figs. 11 and 12, it will be seen that the hinge construction illustrated therein comprises hinge plates 100 and 102, each secured 30 by suitable bolts 104 and 106 to a door section. The hinge plate 100 has curled ears 108 spaced apart to receive the curled ear 110 of hinge plate 102. A hinge pin 112 passes through the curled ears 108 and 110 and forms a pivotal connection 40 therebetween.

A tubular member 114 is welded to hinge plate 102 and its ear 110 as indicated at 116 and 118 and forms a socket for receiving the shaft 120 of a track roller 122.

45 The sheave or idler illustrated in Fig. 5 is illustrative of a wide variety of sheaves or idlers which may be utilized in our construction. This sheave or idler comprises a pair of plates 124 and 126 secured together by bolts 128 and supported on a mounting stud 130. Roller bearings 132 are interposed between the plates 124 and 126 and stud 130, the latter having an annular rib 134 located between the two sets of roller bearings and serving to prevent lateral movement 50 of the sheave relative to its stud.

55 While in the first embodiment illustrated and described the trolley 56 comprises two rollers mounted on a common shaft, an alternative construction may be employed. In the embodiment of Figs. 8, 9, and 10, a single cupped roller is used.

60 From the foregoing it will be apparent that we have provided a simple and inexpensive overdoor especially adapted for installation in buildings where the space above the door opening is 65 a minimum. Our invention, however, is not limited to use in such buildings but is equally capable of use in buildings having ample space above the door opening for the usual overdoor installation. In fact, our novel door is equal in 70 all respects to the conventional overdoor for use in buildings having ample headroom and provides a universal door structure which is adaptable to all situations.

75 While we have stressed the utilization of our door in existing buildings with low headroom

above the door opening, it is also advantageous with present building costs to provide a door suitable for new construction having minimum headroom and therefore costing a minimum to build.

While we have illustrated and described in detail only a single embodiment of our invention it is to be understood that our invention is not limited to the particular construction shown but may assume numerous other forms and includes all variations, modifications, and equivalents coming within the scope of the appended claims.

We claim:

1. The combination with an overdoor adapted to close an opening in a building and two tracks attached to said building, said tracks being positioned adjacent the opening at opposite sides thereof in a plane substantially parallel to the vertical edge of said opening and having a vertical portion adjacent said vertical edge, a horizontal portion extending away from said opening, and a curved portion connecting said vertical and horizontal portions, of a guiding and pivoting mechanism, said mechanism comprising first brackets pivotally connected to the upper corners of said overdoor, a second bracket secured to each of said first brackets, a track roller carried by each of said second brackets, said track rollers being movable along and guided in said tracks, a trolley carried by each of said second brackets, said trolleys being located rearwardly of said tracks, a third bracket attached to each track, a tripper bar carried by each third bracket, and a guide bar carried by each third bracket, said guide bars being located rearwardly of said tripper bars, said bars being disposed rearwardly of said tracks and arranged to engage opposite sides of said trolleys and curved away from said tracks in a downward direction at a radius of curvature less than the radius of curvature of said curved portion, whereby the trolleys bear against the guide bars to swing said second brackets about their track rollers and cause the upper portion of said overdoor to be guided in an arc closely approaching the curved portion of said tracks during the initial movement of said overdoor from the closed position.

2. The combination with an overdoor adapted to close an opening in a building and two tracks attached to said building, said tracks being positioned adjacent the opening at opposite sides thereof in a plane substantially parallel to the vertical edge of said opening and having a vertical portion adjacent said vertical edge, a horizontal portion extending away from said opening, and a curved portion connecting said vertical and horizontal portions, of a guiding and pivoting mechanism, said mechanism comprising first brackets pivotally connected to the upper corners of said overdoor, a second bracket secured to each of said first brackets, a track roller carried by each of said second brackets, said track rollers being movable along and guided in said tracks, a trolley carried by each of said second brackets, said trolleys being located rearwardly of said tracks, a third bracket attached to each track, a tripper bar carried by each third bracket, and a guide bar carried by each third bracket, said guide bars being located rearwardly of said tripper bars, said bars being disposed rearwardly of said tracks and arranged to engage opposite sides of said trolleys and curved away from said tracks in a downward direction at a radius of curvature less than the radius of curvature of said curved portion, whereby the trolleys bear against the

guide bars to swing said second brackets about their track rollers and cause the upper portion of said overdoor to be guided in an arc closely approaching the curved portion of said tracks during the initial movement of said overdoor from the closed position, and during the final movement of said overdoor from opened to closed position the trolleys bear against said tripper bars to swing said second brackets about their track rollers to cause the upper portion of said overdoor to be guided in an arc closely approaching the curved portion of said track and to hold the upper portion of said overdoor in closed position against horizontal forces applied to the upper portion.

3. An overdoor having tracks with vertical and horizontal portions and connecting curved portion located adjacent a door opening, a door mounted on rollers associated with said tracks, said door having an upper end which in closed position has its upper edge spaced a considerable distance forwardly of the curved portions of said track, a pair of first brackets pivotally connected to the upper end of said door, a second bracket secured to each of said first brackets, a track roller carried by each of said second brackets, said track rollers being movable along and guided in said tracks, a trolley carried by each of said second brackets, said trolley being located rearwardly of said tracks, a third bracket attached to each of said tracks, an arcuate tripper bar carried by each of said third brackets, a guide bar carried by each of said third brackets, said guide bar being located rearwardly of said tripper bar, said guide and tripper bars having a radius of curvature less than the radius of curvature of said curved portions of the tracks are being disposed rearwardly of said curved portions, said bars being curved away from said tracks in a downwardly direction with the upper end of the tripper bars substantially tangent to the underside of said tracks, whereby the upper edge of said door is positively hinged and pivoted backwardly toward said curved portion of said track so that the upper edge follows the track closely when the door is opened, and, when the door is closed, the upper edge follows the track closely until the trolley passes between the tripper bar and the guide bar whereupon the upper edge of the door is positively hinged and pivoted forwardly away from the curved portion of the track and pressed tightly against the jamb of the door.

4. The combination with an overdoor adapted to close an opening in a building and two tracks attached to said building, said tracks being positioned adjacent the opening at opposite sides thereof in a plane substantially parallel to the vertical edge of said opening, and having a vertical portion adjacent said vertical edge, a horizontal portion extending away from said opening, and a curved portion connecting said vertical and horizontal portions of a guiding and pivoting mechanism, said mechanism comprising a pair of first brackets pivotally connected to the upper corners of said overdoor, a second bracket secured to each of said first brackets, a track roller carried by each of said brackets, said track rollers being movable along and guided in said tracks, a trolley carried by each of said brackets, said trolleys being located rearwardly of said tracks, a third bracket attached to each track, a tripper bar carried by each third bracket, and a guide bar carried by each third bracket, said guide bar being located rearwardly of said tripper

bar, said bars being disposed to engage opposite sides of said trolleys and curved away from said tracks in a downward direction at a radius of curvature less than the radius of curvature of said curved portions, said bars being disposed rearwardly of said curved portions.

5. The combination with an overdoor adapted to close an opening in a building and two tracks attached to said building, said tracks being positioned adjacent the opening at opposite sides thereof in a plane substantially parallel to the vertical edge of said opening and having a vertical portion adjacent said vertical edge, a horizontal portion extending away from said opening, and a curved portion connecting said vertical and horizontal portions of a guiding and pivoting mechanism, said mechanism comprising a pair of first brackets pivotally connected to the upper corners of said overdoor, said first brackets having an arcuate slot formed therein, a second 20 bracket disposed adjacent each of said first brackets, pin means pivotally connecting said adjacent first and second brackets, a bolt adapted to pass through each of said second brackets and said slot of the adjacent first brackets, said bolts being slidable along the slots when said first and second brackets are rotated relatively to one another about said pin means, means associated

with said bolt to secure the adjacent first and second brackets against relative rotation, a track roller carried by each of said brackets, said track rollers being movable along and guided in said tracks, a trolley carried by each of said brackets, said trolleys being located rearwardly of said tracks, a third bracket attached to each track, a tripper bar carried by each third bracket, and a guide bar carried by each third bracket, said 10 guide bar being located rearwardly of said tripper bar, said bars being disposed to engage opposite sides of said trolleys and curved away from said tracks in a downward direction at a radius of curvature less than the radius of curvature of said curved portions, said bars being disposed rearwardly of said curved portions.
